Fig. 1

Fig. 2

<img alt="Technical cross-sectional diagram of a mechanical assembly, labeled Fig. 3. The diagram shows a housing with various internal components including gears, bearings, and a piston-like part labeled 'a'. Numerous parts are numbered with reference numerals such as 12, 18, 21, 22, 23, 24, 26, 27, 28, 29, 31, 32, 36, 37, 38, 39, 41, 47, 51, 53, 56, 57, 58, 61, 62, 63, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 500, 501, 502, 503, 504, 505, 506, 507, 508, 509, 510, 511, 512, 513, 514, 515, 516, 517, 518, 519, 520, 521, 522, 523, 524, 525, 526, 527, 528, 529, 530, 531, 532, 533, 534, 535, 536, 537, 538, 539, 540, 541, 542, 543, 544, 545, 546, 547, 548, 549, 550, 551, 552, 553, 554, 555, 556, 557, 558, 559, 560, 561, 562, 563, 564, 565, 566, 567, 568, 569, 570, 571, 572, 573, 574, 575, 576, 577, 578, 579, 580, 581, 582, 583, 584, 585, 586, 587, 588, 589, 590, 591, 592, 593, 594, 595, 596, 597, 598, 599, 600, 601, 602, 603, 604, 605, 606, 607, 608, 609, 610, 611, 612, 613, 614, 615, 616, 617, 618, 619, 620, 621, 622, 623, 624, 625, 626, 627, 628, 629, 630, 631, 632, 633, 634, 635, 636, 637, 638, 639, 640, 641, 642, 643, 644, 645, 646, 647, 648, 649, 650, 651, 652, 653, 654, 655, 656, 657, 658, 659, 660, 661, 662, 663, 664, 665, 666, 667, 668, 669, 6610, 6611, 6612, 6613, 6614, 6615, 6616, 6617, 6618, 6619, 6620, 6621, 6622, 6623, 6624, 6625, 6626, 6627, 6628, 6629, 6630, 6631, 6632, 6633, 6634, 6635, 6636, 6637, 6638, 6639, 6640, 6641, 6642, 6643, 6644, 6645, 6646, 6647, 6648, 6649, 66410, 66411, 66412, 66413, 66414, 66415, 66416, 66417, 66418, 66419, 66420, 66421, 66422, 66423, 66424, 66425, 66426, 66427, 66428, 66429, 66430, 66431, 66432, 66433, 66434, 66435, 66436, 66437, 66438, 66439, 66440, 66441, 66442, 66443, 66444, 66445, 66446, 66447, 66448, 66449, 66450, 66451, 66452, 66453, 66454, 66455, 66456, 66457, 66458, 66459, 66460, 66461, 66462, 66463, 66464, 66465, 66466, 66467, 66468, 66469, 66470, 66471, 66472, 66473, 66474, 66475, 66476, 66477, 66478, 66479, 66480, 66481, 66482, 66483, 66484, 66485, 66486, 66487, 66488, 66489, 66490, 66491, 66492, 66493, 66494, 66495, 66496, 66497, 66498, 66499, 664100, 664101, 664102, 664103, 664104, 664105, 664106, 664107, 664108, 664109, 664110, 664111, 664112, 664113, 664114, 664115, 664116, 664117, 664118, 664119, 664120, 664121, 664122, 664123, 664124, 664125, 664126, 664127, 664128, 664129, 664130, 664131, 664132, 664133, 664134, 664135, 664136, 664137, 664138, 664139, 664140, 664141, 664142, 664143, 664144, 664145, 664146, 664147, 664148, 664149, 664150, 664151, 664152, 664153, 664154, 664155, 664156, 664157, 664158, 664159, 664160, 664161, 664162, 664163, 664164, 664165, 664166, 664167, 664168, 664169, 664170, 664171, 664172, 664173, 664174, 664175, 664176, 664177, 664178, 664179, 664180, 664181, 664182, 664183, 664184, 664185, 664186, 664187, 664188, 664189, 664190, 664191, 664192, 664193, 664194, 664195, 664196, 664197, 664198, 664199, 664200, 664201, 664202, 664203, 664204, 664205, 664206, 664207, 664208, 664209, 664210, 664211, 664212, 664213, 664214, 664215, 664216, 664217, 664218, 664219, 664220, 664221, 664222, 664223, 664224, 664225, 664226, 664227, 664228, 664229, 6642200, 6642201, 6642202, 6642203, 6642204, 6642205, 6642206, 6642207, 6642208, 6642209, 6642210, 6642211, 6642212, 6642213, 6642214, 6642215, 6642216, 6642217, 6642218, 6642219, 66422100, 66422101, 66422102, 66422103, 66422104, 66422105, 66422106, 66422107, 66422108, 66422109, 66422110, 66422111, 66422112, 66422113, 66422114, 66422115, 66422116, 66422117, 66422118, 66422119, 66422120, 66422121, 66422122, 66422123, 66422124, 66422125, 66422126, 66422127, 66422128, 66422129, 664221200, 664221201, 664221202, 664221203, 664221204, 664221205, 664221206, 664221207, 664221208, 664221209, 664221210, 664221211, 664221212, 664221213, 664221214, 664221215, 664221216, 664221217, 664221218, 664221219, 664221220, 664221221, 664221222, 664221223, 664221224, 664221225, 664221226, 664221227, 664221228, 664221229, 6642212200, 6642212201, 6642212202, 6642212203, 6642212204, 6642212205, 6642212206, 6642212207, 6642212208, 6642212209, 6642212210, 6642212211, 6642212212, 6642212213, 6642212214, 6642212215, 6642212216, 6642212217, 6642212218, 6642212219, 6642212220, 6642212221, 6642212222, 6642212223, 6642212224, 6642212225, 6642212226, 6642212227, 6642212228, 6642212229, 66422122200, 66422122201, 66422122202, 66422122203, 66422122204, 66422122205, 66422122206, 66422122207, 66422122208, 66422122209, 66422122210, 66422122211, 66422122212, 66422122213, 66422122214, 66422122215, 66422122216, 66422122217, 66422122218, 66422122219, 66422122220, 66422122221, 66422122222, 66422122223, 66422122224, 66422122225, 66422122226, 66422122227, 66422122228, 66422122229, 664221222200, 664221222201, 664221222202, 664221222203, 664221222204, 664221222205, 664221222206, 664221222207, 664221222208, CIGAR LIGHTER

John Sinko, Chicago, Ill.

Application June 11, 1935, Serial No. 25,968

19 Claims. (Cl. 219—32)

This invention relates to cigar lighters of the type used in automobiles, and more particularly to the kind known as the "wireless type" because a separable plug which is first heated in a socket 5 may then be removed from the socket for lighting a cigar, cigarette or pipe.

In the form of this invention chosen for illustration, there is provided a tubular socket member having fixed therein an outwardly opening 10 cup member at the base of which, and insulated therefrom, is a suitable contact member connected to a wire extending out through the rear end of the socket. Extending into the front end of the socket is the plug member which includes 15 a contact ring engaging said cup member and pressing against a spring in said plug which normally keeps said plug out of contact with said contact member. The plug also carries a heating element which is connected to said ring and 20 which makes contact with said contact member when the plug is pressed inwardly against the spring. The handle of the plug member is translucent and so arranged that when the ignition element becomes incandescent the handle will 25 glow, the glow preferably being concentrated around its rim.

Cigar lighters of the general type in which a plug carrying the ignition element is removed after the ignition element has been heated, have 30 been known for some time, and in fact one of these is disclosed in my co-pending application, Serial No. 724,849, of which the present lighter may be considered an improvement.

It is an object of the present invention to provide 35 a cigar lighter of simplified and yet thoroughly dependable construction.

It is a further object to provide a cigar lighter in which both the handle and the heating unit may be very easily removed for replacement or 40 repair.

It is an additional object of this invention to provide a translucent handle having its surface which faces the ignition element so shaped as to direct the rays of light to the shoulder at the base of the handle.

Another object is to have both of the necessary contacts made by positive pressure, as distinguished from the mere sliding contact heretofore 45 common.

Other advantages and objects of my invention will be apparent from the following description, taken with the drawing, in which:

Fig. 1 is an elevational view of the form of the 50 invention chosen for illustration, showing its

relationship to the dashboard of an automobile, or other supporting member.

Fig. 2 is an end elevation of the structure shown in Fig. 1, the connecting wire being shown in section.

Fig. 3 is an enlarged sectional view of the lighter shown in Fig. 1.

Fig. 4 is a section substantially along the line 4—4 of Fig. 3.

Fig. 5 is a section substantially along the line 10 5—5 of Fig. 3.

Fig. 6 is a section substantially along the line 6—6 of Fig. 3.

Fig. 7 is a perspective view of the contact insert shown in Fig. 3; and

Fig. 8 is a sectional view of a modified shape 15 of handle.

Although this invention may take numerous forms, only one has been chosen for illustration, together with a slightly modified handle therefor. In this form there is provided a tubular socket member 11 which, at its front and open end, is provided with a flange 12 which may rest against the dashboard 13 of an automobile or other support through which the socket member 11 extends. To hold the socket member in place there is a U-shaped clamp 14 which is provided at its end with an aperture through which a threaded bushing 16 on the back end of the socket 11 extends. A suitable nut 17 screws on the bushing 16 against a lock washer 18 bearing on the U-shaped clamp 14. Thus it is seen that tightening the nut 17 tightens the flange 12 against the front of the dashboard 13 and likewise tightens the clamp 14 against the back of 30 the dashboard. It should be understood, of course, that the socket 11 may be secured in place in any other manner that might be desired. The bushing 16 may be secured to the socket 11 in any suitable manner, as by having a reduced neck portion extending therethrough and turned over, as illustrated in Fig. 3. A steel disc 21 with a raised rim 20 lays in the back end 19 of the socket 11, and is rigidly secured in position by crimping the top of the bushing 16. This disc 40 provides a slightly resilient mounting for and insures a positive engagement with one of the terminal members, as will be hereinafter explained.

Located within the socket 11 and at its inner end is a suitable contact unit, such as is shown in Fig. 7. This unit is preferably made up of an inner cup 22, an outer cup 23 and a contact element or cup 24, all secured together by a terminal bushing 26 which has a reduced neck portion 50 55

turned over as shown. The terminal bushing 26 and the contact element 24 should both be insulated from the cups 22 and 23, as by suitable layers of mica 27 as illustrated. There may also be a washer of insulation between the discs 27 of mica to center the bushing 26 with respect to the cups, but this is not necessary since the mica discs themselves perform this function. The inner cup 22 is preferably provided with slots 28 through which are bent tongues 29 cut from the socket 11. A wire, preferably made up of the strands 31, is secured within the bushing 26, as by soldering or crimping, and extends through the bushing 16, being insulated therefrom by the usual insulating covering 32 on the wire. The cup 22 not only serves as a mounting for cup 23 by receiving tongues 29 in slots 28, but also serves to space the cup 23 away from the far end of the socket to permit the use of an elongated bushing 26 to carry a substantial length of wire 31 and serve as a housing for the bushing.

In assembling the socket unit the wire is first attached to the contact unit shown in Fig. 7 and then threaded through the socket 11 and bushing 16 and drawn out until the cup 22 strikes the reinforcing disc 21. The tongues 29 are then bent over, passing inwardly through the slots 28, thus securing the contact unit in place. By shaping the washer 21, as shown, the cup 22 is positioned in the best location for coaction with the tongues 29, and a slight degree of resiliency prevents any looseness. Furthermore, a bearing surface for the cup 22 is formed by rim 20 perpendicular to the side walls of socket 11, thus avoiding difficulties due to the rounded inner corners of the socket 11. The outer cup 23 is preferably provided with holes 33 which are aligned with holes 34 in the socket 11, thereby ventilating the inside of the outer cup 23 even when the plug is in place.

The plug includes the handle 36 which may be made of glass or any other material, preferably translucent so that it will glow when the heating element is heated to incandescence. A sleeve 31 of insulating material is preferably screwed onto the handle 36, and a support member 38 is screwed into the other end of the sleeve 31. The plug is retained in the socket in any suitable manner as by a leaf spring 35 formed as a tongue cut from the socket 11, and bearing on the side of the sleeve 31. The support member 38 may comprise a rim having formed integrally therewith the spokes 39 at the center of which is formed an elongated hub 41. To this support member 38 is secured a heating unit 42 which is preferably of a standard form so that it may be readily interchanged with other units. This heating unit may desirably include an inwardly facing cup 43 and a helix of resistance wire or ribbon 44 secured at one end to the sleeve 43 and at the other end to the head 46 of a bolt 47 which passes through the cup 43 and the hub 41. The cup 43 has a suitable aperture 48 in its base which may be the space between spokes 50 forming the base. A collar 45 rests on the center support for the spokes 50 to carry the head 46 of the bolt 47 within the cup. The heating element 44 is electrically insulated from the base of the cup 43 including the said spokes, as by a sheet of mica 49 cut to register with the spokes and fitting under the collar 45. On the back of the base of the cup 43 is another insulating washer 51 which may be formed of mica, against which there is a nut 52 which clamps the cup 43 against the heating element 44. Another nut 53, also

screwed on the bolt 47, in turn clamps the nut 52 against the hub 41, thereby rigidly mounting the cup 43 on the support member.

Carried between the support member 38 and the cup 43 is a contact ring 56 which may be guided by a cylindrically shaped flange 57 extending forwardly between the inner and outer edges of the ring, and sliding inside of the rim of support member 38. Between the ring 56 and the spokes 39 is positioned a spring 58 under compression which tends to separate the support member from the contact ring 56 pushing the contact ring against the cup 43.

As the plug is inserted in the socket 11 the contact ring 56 engages the outer cup 23 of the contact unit fixed at the inner end of the socket 11. The spring 58 normally prevents further inward movement of the rest of the plug, but when sufficient pressure is exerted on the handle 36 to overcome the force of the spring 58, all of the plug except the contact ring 48 is moved further inwardly until the cup 43 contacts the fixed contact element 24. A circuit is thus completed from the wire 31 through the bushing 26, the contact element 24, the cup 43, the heating element 44, bolt 47, spokes 39, sleeve 38 or spring 58, to the contact ring 56, and from thence through the outer cup 23 and the inner cup 22 to the reinforcing disc 21 and to ground through the bushing 16 and the clamp 14 or the socket 11 and flange 12.

It should be noted that contact ring 56 is preferably spaced from the walls of socket 11 so that there can be no chance of its not seating properly on the cup 23. It therefore contacts the cup 23 with positive pressure exerted by the spring 58, this pressure being at its maximum when the spring is compressed by moving the plug to heating position. The cup 23 may also be spaced from the side walls of socket 11 or it may be crimped, as at 60, to furnish a dependable seat for the contact ring 56 even though it is of smaller diameter than the bore of the socket 11. By making the support member 38 likewise smaller in diameter than the interior of socket 11, the sliding of metal on metal is prevented, the sleeve 31 being made of a relatively soft though rigid material such as that known commercially as bakelite. This results in an unusually smooth action in sliding the plug into the socket.

The handle 36 is preferably made entirely of a translucent material, though if preferred only certain portions thereof may be translucent. In any event, it is preferred that the peripheral portion at the base be translucent and so shaped as to concentrate along the annular shoulder 61 most of the light entering it from the ignition element. The advantage of this is that even though a person hide the main part of the handle with his hand, some portion of the annular shoulder 61 is almost certain to be visible. This shoulder in fact comprises an annular flange at the base of the handle which glows and which is always in view.

Two preferred shapes for the inner faces of the handle are illustrated. In both of these forms it will be noted that the peripheral portion 62 of the inner face is positioned to face substantially directly toward the ignition element, with the result that nearly all the light striking this portion passes through the surface and continues on to the shoulder 61, as indicated by the dotted line "a" in Fig. 3. In this form it is possible that the inner surface, or at least the portion 62 thereof, be smooth or polished. And this

portion may be considered a lens surface for focusing the rays on the shoulder 61. The curvature of this surface may be continued further if preferred. The more central portion 63 of the inner surface in Fig. 3 is of conical shape and inclined at such an angle that a large portion of the light striking this surface, as indicated by the line "b", is reflected thereby to strike the corresponding portion of this surface on the opposite side thereof, where a portion of the light striking this surface passes therethrough and is refracted by the translucent material so as to strike the lower portion of the shoulder 61. Where the light first strikes the surface 63 along the line "b", that portion of it which enters the surface is sharply deflected by refraction so that it also reaches the shoulder 61 rather than passing out through the far end of the handle. The lines *a* and *b* have not been drawn with the idea of representing the course of light exactly, but merely to illustrate the general principle. It should be understood, of course, that the degree of refraction will depend upon the material of which the handle 36 is made.

In the Fig. 8 form especially, it may be preferred that the concave portion 63 of the inner surface be roughed, as by grinding. In this event, the portion 62 may be reduced to bring the surface 63 closer to the shoulder 61, this being desirable when the surface 63 acts as a secondary light source.

It may be observed that the space between the sleeve 38 and the hub 41 forms an annular passage which directs most of the light from the ignition element toward the outer portion of the inner surface. The result is that even if this outer portion of the surface is perpendicular to the axis of the socket 11, the shoulder 61 will be fairly well illuminated. This alone would make a very desirable lighter and may be considered as within the scope of this invention, but this invention goes further and contemplates causing this annular shoulder to glow with even greater brilliance. It should be understood, of course, that some light striking the handle 36 at a point nearer the center than the line *b* will pass therethrough and cause the far end of the handle to glow slightly so that if in some unusual manner the entire shoulder 61 is covered up, the glow on the handle may still be seen.

It is to be understood that numerous details of the construction shown may be altered or omitted without departing from my invention as defined by the following claims.

I claim:

1. A cigar lighter including a tubular socket member having a base contact and a stop contact within said socket; a plug removably held within said socket and including a support member, a heater unit secured thereto and including a cup spaced forwardly therefrom, a positioning ring for engaging said stop and movable relatively to said plug between said support member and said cup, a spring engaging said ring and pushing the rest of the plug rearwardly therefrom and away from said contact, and a flange formed on said ring and extending rearwardly therefrom, for guiding it by a sliding engagement with said support member, said plug contacting said base contact as it is pushed forward against the tension of said spring.

2. A cigar lighter including a socket member having a base contact and a stop contact within said socket; a plug removably held within said socket and including a support member, a heater

unit secured thereto, a positioning ring for engaging said stop contact and movable lengthwise relatively to said support member, a spring engaging said ring and pushing the rest of the plug rearwardly therefrom and away from said contact, and a flange formed on said ring and extending rearwardly therefrom, for guiding it by a sliding engagement with said support member, said plug contacting said base contact as it is pushed forward against the tension of said spring.

3. A cigar lighter including a tubular socket member provided with a base-contact and a stop contact in said socket, said member being adapted for insertion into the dashboard of a car; a plug removably held in said socket and including a support member, a heater unit secured thereto and including a cup spaced forwardly therefrom, a positioning ring for engaging said stop and movable relatively to said plug between said support member and said cup, a spring engaging said ring and pushing the rest of the plug rearwardly therefrom and away from said contact, said plug contacting said base contact as it is pushed forward against the tension of said spring.

4. A cigar lighter including a tubular socket member provided with a base-contact and a stop contact within said socket; a plug removably held within said socket and including a support member, a heater unit secured thereto, a positioning ring for engaging said stop and movable lengthwise relatively to said support member, a spring engaging said ring and pushing the rest of the plug rearwardly therefrom, said plug contacting said base contact as it is pushed forward against the tension of said spring.

5. A cigar lighter including a socket member provided with a base-contact and a stop contact within said socket; a plug removably held in said socket and including a support member having a rim and a transverse portion, a heater unit secured to said transverse portion and including a cup spaced forwardly from said rim, a positioning ring for engaging said stop and movable relatively to said plug between said support member and said cup, a spring compressed between said ring and said transverse portion and pushing the rest of the plug rearwardly from said ring and away from said contact portion, and a flange formed on said ring and extending rearwardly therefrom for guiding it by a sliding engagement with said support member, said plug contacting said base contact as it is pushed forward against the tension of said spring.

6. A cigar lighter including a socket, a contact and a stop in said socket; a plug removably held in said socket and including a support member having a rim and a transverse portion, a heater unit secured to said transverse portion and including a cup spaced forwardly from said rim, a positioning ring for engaging said stop and movable relatively to said plug between said support member and said cup, a spring compressed between said ring and said transverse portion and pushing the rest of the plug rearwardly from said ring and away from said contact portion; said plug contacting said contact as it is pushed forward against the tension of said spring.

7. A plug for a cigar lighter comprising a handle, a sleeve of insulating material secured to said handle, a support member secured to said sleeve and including a rim and a hub connected together by spokes, a heating unit secured rigidly to said hub, and a contact ring guided by said rim and limited in its movement by said ignition unit, and

a spring urging said contact ring against said ignition unit.

8. A plug for a cigar lighter comprising a handle, a sleeve of insulating material secured to said handle, a support member secured to said sleeve and including a rim and a hub connected together by spokes, a heating unit secured rigidly to said hub, and a contact ring guided by said rim and limited in its movement by said ignition unit, and a spring compressed between said spokes and said contact ring urging said contact ring against said ignition unit.

9. A cigar lighter including a tubular socket member, a contact unit within said socket member including an inwardly facing cup member, an outwardly facing contact element mounted thereon and insulated therefrom, and a terminal bushing mounted on the inside of said cup member and insulated therefrom, but connected to said contact element, and an elongated conduit bushing in the inner end of said socket through which is passed an insulated wire connected to said terminal bushing, and an outwardly facing cup member carried by and rigidly secured to said inwardly facing cup member and connected to said socket member.

10. A cigar lighter including a tubular socket member, a contact unit within said socket member including an inwardly facing cup member, an outwardly facing contact element mounted thereon and insulated therefrom, and a terminal bushing mounted on the inside of said cup member and insulated therefrom, but connected to said contact element, and an elongated conduit bushing in the inner end of said socket through which is passed an insulated wire connected to said terminal bushing, and an outwardly facing cup member carried by and rigidly secured to said inwardly facing cup member and connected to said socket member, and a plug removably carried by said socket member and including a heating element, a contact element therefor aligned with said first named contact element, and a contact ring engaging said outwardly facing cup and bearing against one end of a spring, the other end of which bears against said plug to normally space said contact elements apart.

11. A cigar lighter including a tubular socket member, a dished end plate within said socket member engaging the central portion of the rear end of the socket and spaced forwardly therefrom at its periphery, a contact unit within said socket member including an inwardly facing cup member engaging the periphery of said end plate, an outwardly facing contact element mounted thereon and insulated therefrom, and a terminal bushing mounted on the inside of said cup member and insulated therefrom, but connected to said contact element, and an elongated conduit bushing in the inner end of said socket through which is passed an insulated wire connected to said terminal bushing, and an outwardly facing cup member carried by and rigidly secured to said inwardly facing cup member and connected to said socket member.

12. A cigar lighter including a tubular socket member, a dished end plate within said socket member engaging the central portion of the rear end of the socket and spaced forwardly therefrom at its periphery, a contact unit within said socket member including an inwardly facing cup member engaging the periphery of said end plate, an outwardly facing contact element mounted thereon and insulated therefrom, and a terminal bushing mounted on the inside of said cup member,

and a tongue formed on said socket member and bent around a portion of said cup member to hold it against said end plate.

13. A cigar lighter including a metal socket, a plug comprising a handle, a sleeve of insulating material secured to said handle, a support member secured to said sleeve and including a rim and a hub connected together by spokes, an ignition unit secured rigidly to said hub, and a contact ring guided by said rim and limited in its movement by said ignition unit, and a spring urging said contact ring against said ignition unit, said rim, ring and ignition unit being of smaller diameter than the internal diameter of said socket and the external diameter of said sleeve to prevent metal rubbing on metal as said plug is slid into said socket.

14. A heater unit, adapted to be mounted on a removable handle member and inserted into a socket member having a base terminal and insulated therefrom an inwardly extending wall-terminal, comprising: a heating coil provided with a rearwardly extending conducting stem and a base-terminal contacting member; a collar having an inwardly extending flange forming a seat, and having an outwardly extending flange adapted to contact the wall-terminal of the socket; a conducting compression spring encircling said stem and resting in said seat; and a conducting support member forming a seat for the outer end of said spring, said member being connected to the stem and provided with connecting means for mounting on the handle member.

15. A device as specified in claim 14, in which the collar is slidably mounted in the support member, and the support member is secured to the stem against rotation with respect thereto.

16. A device as specified in claim 14, in which the stem is threaded at its outer end and provided with a flat side adapted to slide into non-rotatable engagement with an opening in the conducting support member, and a nut is provided to draw the stem through the said opening and partially compress the spring.

17. A heater unit, adapted to be mounted on a removable handle member and inserted into a socket member having a base terminal and insulated therefrom an inwardly extending wall-terminal, comprising: a heating member having a cup adapted to contact the base-terminal when thrust inwardly, a resistance coil having one end connected to said cup and the remainder of said coil insulated therefrom, and a rearwardly extending conducting stem connected to the opposite end of said coil and fixedly mounted on and insulated from the cup; a collar having an inwardly extending flange forming a seat, and having an outwardly extending flange adapted to contact the wall-terminal of the socket; a conducting compression spring encircling said stem and resting in said seat; and a conducting support member forming a seat for the outer end of said spring, said member being connected to the stem and provided with connecting means for mounting on the handle member.

18. A cigar lighter including a tubular socket member adapted to extend through a perforated panel to form one electrical terminal for a plug member and having a base contact member insulated therefrom; and a plug removably held within said socket including a handle adapted to be fully inserted into the socket, an insulating sleeve threaded to said handle, a support member threaded to the front end of said sleeve, a heater unit secured to said support member, a

positioning ring having a flange for engaging said socket member to limit its forward travel and movable lengthwise relatively to said sleeve and support member, and a spring in front of said handle engaging said ring and urging the rest of the plug rearwardly in said socket, said plug contacting said base contact member as it is pushed forward against the tension of said spring.

19. In a cigar lighter having a metal tubular socket, a plug comprising: a handle; a hollow sleeve of insulating material secured to the front of said handle and adapted to be inserted into said socket; a support member threaded to the

inner front end of said sleeve and including a rim and a hub connected together by spokes; an ignition unit secured rigidly to said hub; a slide ring carried by said sleeve so as to serve as a guide for the plug, said ring having an internally directed front flange moveable towards and away from said ignition unit; and a spring in front of said handle engaging said flange so as to urge the ring forwardly, said rim, flange and ignition unit being of smaller diameter than the internal diameter of said socket to permit the plug to be slid into the socket. 5 10

JOHN SINKO.

CERTIFICATE OF CORRECTION.

Patent No. 2,111,302.

March 15, 1938.

JOHN SINKO.

It is hereby certified that error appears in the printed specification of the above numbered patent requiring correction as follows: Page 4, second column, lines 71, 72, 73 and 74 inclusive, claim 18, for the words "within said socket including a handle adapted to be fully inserted into the socket, an insulating sleeve threaded to said handle, a support member" read within said socket including a handle, an insulating sleeve threaded to said handle and adapted to be fully inserted into the socket, a support member; and that the said Letters Patent should be read with this correction therein that the same may conform to the record of the case in the Patent Office.

Signed and sealed this 15th day of September, A. D. 1938.

(Seal)

Henry Van Arsdale
Acting Commissioner of Patents.
